Des. 229,528

Patented Dec. 11, 1973

229,528

ICE CREAM DISPLAY CABINET

Bernard L. Rothbardt, Sherman Oaks, Calif., assignor to
Baskins-Robbins Inc., Burbank, Calif.

Filed Sept. 3, 1971, Ser. No. 177,927

Term of patent 14 years

Int. Cl. D6—04

U.S. Cl. D6—168

FIG. 1.

FIG. 2.

FIG. 3.

FIG. 4.

FIG. 1 is a top plan view of an ice cream display cabinet showing my new design;

FIG. 2 is a front elevational view;

FIG. 3 is a rear elevational view; and

FIG. 4 is an elevational view showing one of the two identical sides.

I claim:

The ornamental design for an ice cream display cabinet, as shown and described.
